UNITED STATES PATENT OFFICE.

DERMOT J. MOONEY, OF LONDON, ENGLAND.

AIRCRAFT-FRAMEWORK MEMBER.

Application filed January 22, 1926, Serial No. 83,106, and in Great Britain December 10, 1924.

The present invention relates to framework members for aircraft which may find embodiment in a strut, spar, or boom.

It is an object of the invention to provide a framework member which will combine lightness in weight with strength and durability of construction, and a framework member which may be manufactured with comparative economy.

10 Preferably the framework members are hollow, and formed of a plurality of metal ribbons or strips, the edges of which offer mating lap joints.

Preferably also the members are connected at the lap joints in such a manner that the hollow construction is braced against crushing and retained against expansion. In other words, the hollow frame members are reinforced transversely by 20 members which act both as struts and ties.

In the case of relatively large spars, the frame members may be formed of a plurality of metallic strips or ribbons corrugated longitudinally to strengthen the same, and 25 connected together either directly or through the intermediacy of corrugated connecting webs. These webs may be of sectional construction and include a number of web members held together by lap joints.

In other embodiments of the invention, particularly when the invention is applied to relatively massive spars, strengthening means may be provided in the form of dia- 35 phragms or posts disposed either within or without the tubular frame members.

The advantage of the construction is the fact that it dispenses with outer flanges and joints, facilitates assembly, and provides a 40 positive interlock of the frame member sections. Furthermore, rivets are eliminated, center line strut fittings may be conveniently used, and ribs conveniently attached by using the same bolts which secure the booms.

45 With the above noted and other objects in view, the invention consists in certain novel features of construction and combinations and arrangements of parts, as will be more fully hereinafter set forth and pointed out in the claims. The invention may be more fully understood from the following

description in connection with the accompanying drawings, wherein—

Fig. 1 is a fragmentary perspective view 55 of a frame member embodying the invention, the frame member of Fig. 1 illustrating the invention in its most elementary form.

Figs. 2 to 15 inclusive are views in end 60 elevations of other types of frame members embodying the invention, each of said views illustrating a modification.

In Fig. 1 I have illustrated a somewhat elementary embodiment of the invention in 65 which the boom includes a pair of metallic strips 10, 10^a bent longitudinally so that they are approximately three-quarter circular in cross section. The edges of the strips are reversely curved, providing lap joints 70 at 11. The overlapping edges of the sections are similarly contoured so that they snugly fit one within the other, the two sections when joined, providing a frame member of substantially 8-shape in cross section. Transverse connecting bolts 12 are passed through the lap joints 11, these bolts carrying nuts 13 which effectively retain the united sections 10 and 10^a against relative separation. Some means is provided 75 for preventing relative advance of the two sections at the lap joints. This means may conveniently comprise a spacing sleeve 14 encircling the intermediate portion of the bolt 12. Obviously any suitable number of 80 bolts are provided throughout the length of 85 the hollow frame member.

In Fig. 2 I have illustrated a construction similar to Fig. 1, except that the members 10 and 10^a are formed with longitudinally 90 extending depressions 15 defining corrugations 16 which materially strengthen the construction.

In Fig. 3 the members are provided with two depressions 17, defining 3 corrugations 95 18, and rendering each section substantially cross shaped in cross section.

In Fig. 4 I have shown a pair of sections 19 and 20 which are relatively wide and formed with a plurality of corrugations 21. 100 The ends of the members form lap joints at 22, and are connected by bolts and spacing sleeves in the manner above described.

In Fig. 5 the hollow frame members in-

clude metal sections 22 and 23 connected by intermediate webs 24. The webs form lap joints as at 25 with the sections 22, 23. A bolt and spacer sleeve construction similar to that described above is used to couple the webs to the frame sections at the lap joints.

In Fig. 6, corrugated frame sections 26 are connected to webs 27 by lap joints 28, bolts and spacer sleeves passing through the lap joints. In this figure, the frame sections are corrugated to provide a plurality of grooves and ribs, and the webs 27 are also corrugated to strengthen the construction.

The showing of Fig. 7 is substantially the same as the showing of Fig. 6, except that the frame members 29 are formed with a greater number of corrugations than the frame members 26, and the webs 30 are indented at 31 rather than corrugated through their entire width.

Fig. 8 shows uncorrugated frame members 32 connected by corrugated webs 33, the intermediate portions 34 of the webs in this instance actually contacting and being connected by rivets, bolts or other securing devices 35.

The showing of Fig. 9 is substantially similar to that of Fig. 8, except that I have shown corrugated tubular frame members 36, and have employed a spacing member 37 on the bolt 38 which connects the intermediate portions of the webs 39.

In Fig. 10 the frame members 40 are connected to each other by a series of webs 41. Webs 41 are connected to each other by lap joints 43, bolts 44 and spacers 45. The end webs 41 are connected by lap joints 47 to the frame members 40 in the manner previously described.

In Fig. 11 I have shown frame members 48 of hollow construction, and approximately star shaped in cross section connected by webs 49 which are substantially uniformly corrugated. The space between the webs is materially less than the width of the frame members 48, so that I may employ a pair of external strengthening plates or posts 50 which are riveted as at 51 to the corrugations of the webs 49, and which materially strengthen the construction.

In Fig. 12 I have shown pairs of tubular corner posts 55. The posts of each pair are connected by a web 56. Lap joints 55^a are provided at the junctions between the webs 56 and the corner posts 55. The posts of opposite pairs are connected by series of webs 57 and 58 to each other. Lap joints 57^a are provided where webs 58 and 57 join, and the above described construction of cross bolts 59 and spacing sleeves 60 are utilized at the points where the webs 57, 58 join each other.

As an added feature, I provide at intervals throughout the length of the spar,

crossed strengthening braces 61, the ends of which project into the necks of the tubular corner posts 55, and are held by bolts 62. The crossed braces 61 may be connected as by a rivet or other connecting device 63 at 70 their point of crossing, so that a substantially rigid construction is had.

Fig. 13 illustrates a frame member similar to that of Fig. 12 except that a connecting plate 64 is provided at the point of crossing of the frame members 61, both of the frame members 61 being riveted as at 65 to the plate.

In Fig. 14 I show a construction somewhat similar to that of Fig. 11, except that the bracing means is disposed within the frame member, and the frame member is of approximately uniform width. Here the corrugated posts or frame members 66 are connected by webs 67, the webs being regularly corrugated and defining with the posts, lap joints 68 through which connecting bolts 69 are passed. Instead of using the spacing sleeves however, I prefer to utilize channel plates 70, the flanges 71 of said plates receiving the cross bolts 69, and being riveted as at 72 to the corrugated webs 67.

The showing of Fig. 15 is similar to that of the figure just described, except that a further modified type of spacing and reinforcing means is employed. Here the reinforcing means and spacing means comprises a double H-shape frame including legs 82 and cross bars 73. The connecting bolts 69^a pass through the legs 82 adjacent the ends of the latter, and the webs 67^a are riveted as at 72^a to the legs 82. The cross bars 73 serve as spacers and the frame 82, 73 acts to afford a substantial reinforcement for the tubular spar or strut.

It will be noted that all forms of the aeroplane frame member which I have described, embody certain common features. In every instance the frame member is made up of a plurality of metallic sections which are longitudinally bent and which are connected to each other by lap joints. In every instance also the connecting devices which pass through the lap joints are associated with certain spacer means which in most instances are in the nature of spacing sleeves around the connecting bolts and which are formed to produce shoulders which abut the inner members of opposite lap joints. It will also be noted that in most instances the lap joints are defined by similarly curved portions of the adjoining sections, so that there is a positive interlock at the lap joint independently of the connecting bolts. In every instance the complete frame member is externally corrugated to strengthen the same, and in every case except Fig. 1, the individual sections of the frame members are longitudinally corrugated.

Various changes and alterations might be

made in the general form and arrangement of parts described without departing from the invention. Hence I do not wish to limit myself to the details set forth, but shall consider myself at liberty to make such changes and alterations as fairly fall within the spirit and scope of the appended claims.

I claim:

1. A hollow framework member comprising a plurality of cooperative longitudinal sections, the meeting edge portions of adjacent sections being formed to produce lap joints, at least two of said lap joints being provided and being disposed directly opposite each other, and combined strut and tie means connecting said oppositely disposed lap joints and serving also to secure the members of each of said oppositely disposed lap joints to each other.

2. A hollow framework member comprising a plurality of cooperative longitudinal sections, the meeting edge portions of adjacent sections being formed to produce lap joints, at least two of said lap joints being provided and being disposed directly opposite each other, and combined strut and tie means connecting said oppositely disposed lap joints and serving also to secure the members of each of said oppositely disposed lap joints to each other, said combined strut and tie means extending through said hollow framework member between said oppositely disposed lap joints and having shoulders abutting the inner faces of the inner members of said oppositely disposed lap joints.

3. A hollow framework member comprising a plurality of cooperative longitudinal sections, the meeting edge portions of adjacent sections being formed to produce lap joints, at least two of said lap joints being provided and being disposed directly opposite each other, and combined strut and tie means connecting said oppositely disposed lap joints and serving also to secure the members of each of said oppositely disposed lap joints to each other, said combined strut and tie means comprising a rod extending through said hollow framework member and through alined openings in the members of said oppositely disposed lap joints, spacer means on said rod between the inner members of said oppositely disposed lap joints, and

nuts screwed on the end portions of said rod against the outer members of said oppositely disposed lap joints.

4. A hollow framework member comprising a plurality of cooperative longitudinal sections, the meeting edge portions of adjacent sections being formed to produce lap joints, at least two of said lap joints being provided and being disposed directly opposite each other, and combined strut and tie means connecting said oppositely disposed lap joints and serving also to secure the members of each of said oppositely disposed lap joints to each other, the members of each of said lap joints being similarly formed to interlock adjacent sections together at the joint and so that the edge of each member of said lap joint is supported by the other member of said lap joint.

5. An aircraft framework member comprising a pair of longitudinal hollow frame members open at their inner sides, and web members connecting corresponding edge portions of said hollow frame members, the meeting edge portions of said web members and said hollow frame members being formed to provide lap joints, the lap joints at the edges of each of said hollow frame members being in alinement transversely of said aircraft framework member, and combined strut and tie means connecting said alined lap joints and also serving to secure the members of each of the connected lap joints to each other.

6. An aircraft framework member comprising a pair of longitudinal hollow frame members open at their inner sides, and web members connecting corresponding edge portions of said hollow frame members, the meeting edge portions of said web members and said hollow frame members being formed to provide lap joints, the lap joints at the edges of each of said hollow frame members being in alinement transversely of said aircraft framework member, combined strut and tie means connecting said alined lap joints and also serving to secure the members of each of the connected lap joints to each other, and reinforcing members extending between said hollow frame members and connected with said web members.
